UNITED STATES PATENT OFFICE.

HERBERT W. McMILLAN, OF LACHINE, QUEBEC, CANADA.

DRILLING AND REAMING MACHINE.

Application filed August 1, 1927. Serial No. 209,922.

This invention relates to new and useful improvements in drilling and reaming machines, and the object of the invention is to provide a machine which will be quickly and easily adjusted for drilling and reaming holes in the circumferential and longitudinal seams of boilers, pulp digesters, and like vessels, which may be of cylindrical, conical, or spherical form.

10 Another object is to provide a machine of simple construction which may be easily assembled within the boiler, or like structure, to facilitate the operation of drilling or reaming holes at any desired part of the shell and any angle thereto, so that the cost of such drilling is reduced to a minimum.

According to my invention, the drilling and reaming device is pivotally and slidably mounted in an arm which may be angularly 20 adjusted in a mast rotatably held in position in suitable bearings. The mast is mounted within the shell to be drilled and by moving the drilling mechanism support in a substantially vertical direction within the arm, 25 adjusting the angular position of same, or by rotating the mast about its pivotal supports, the drill may be quickly adjusted so that any holes may be drilled in any part of the shell without moving same. Means are provided 30 for locking the arm at any desired angle and means are provided for raising the drill rotating mechanism and for holding same in any desired position.

In the drawings which show my preferred 35 form of the invention;

Figure 1 is a vertical end elevation of the machine with parts thereof shown in section.

Figure 2 is a vertical part sectional elevation of the machine taken on the line 2—2 40 Figure 1.

Figure 3 is a plan view of the drill and the rotating mechanism therefor.

Figure 4 is a diagrammatic illustration of the machine mounted within part of a 45 digester shell.

Referring more particularly to the drawings, 11 designates the mast members which are spaced from one another and held together by means of the crossheads 12 and 13, positioned respectively at the upper and lower ends of the members. The lower crosshead has a downwardly extending pin 14 which is rotatably held in a footstep bearing 15, secured to a foundation 16. The upper

crosshead is recessed to receive a pin 17 depending from a bearing 18 secured to a beam 19. Pivotally secured to the mast members by means of the pins 21 is the arm 20. The arm comprises two channel-shaped members held apart at their ends by means of the spacing members 22 and 23, said arm being so constructed that it can be moved into a position substantially parallel to the mast. An adjustable connection 24 is provided between the mast and the arm, so that same can be held in any adjusted position. The adjustable connection may consist of a right and left hand threaded bar 25, one end passing through the bottom arm spacing member and the other end through a rotatably mounted bar 26 passing between the mast members. Two guide blocks 27 are slidably mounted one in each of the channel-shaped arm members, and connecting said blocks together is the arch shaped bar 28, 75 the centre of which is connected to one end of a chain 29 which passes over a pulley 30 rotatably secured to the spacer bar at the top of the arm and through a hoisting block 31 suspended from the cross member 80 of the mast. The block 31 shown diagrammatically is for illustrative purposes only and it will be readily understood that any type of hoisting mechanism may be employed. Pivotally secured to the projections 85 32 of the guide blocks are the plates 33 which support the frame 34 which carries the drill actuating mechanism. This mechanism consists mainly of a suitably geared motor 35, secured to the frame, a motor spindle 36, a coupling 37 connecting the spindle to a hollow sleeve 38, which is suitably keyed or connected to drive the shaft 39 and to allow same to slide back and forth in the said sleeve. The sleeve is rotatably mounted on 95 a bearing 40, which may be mounted on the frame. Air cylinders 41 are positioned on either side of the bearing 40 and may be formed integral therewith, as shown. The outer ends 42 of the piston rods working in 100 said cylinders are attached to a crosshead 43, which holds the rotating shaft 39 against thrust bearings 44 positioned on each side of the crosshead. The thrust bearings are held against the crosshead by means of the 105 threaded collars 45 secured to the said shaft 39, so that any movement of the crosshead operated by the air pistons is transmitted

to the shaft 39, which is provided at its free end with a socket 46 to receive the reamer or drill 47. A handle 48 may be secured to the the back or motor end 49 of the frame.

5 The manner of mounting the device for operation is shown diagrammatically in Figure 4. The digester shell 50 is mounted preferably, but not necessarily, concentric with the footstep bearing. The mast is then 10 placed in a substantially vertical position, as shown, and is rotatably anchored to the upper support. It will be readily seen that the arm may be set to any desired angle and in Figure 4 it is shown substantially parallel with the sloping side 51 of the shell 50. The drill actuating mechanism is raised or lowered within the arm and it will also be seen that the frame may be swung at any desired angle to the said arm. The mast 20 being rotatably mounted, allows the drill to be rotated into any part in the circumference of the shell. The air cylinders form a cushioned feeding mechanism for the drill or reamer.

25 The device is very simple in operation and easily erected in position, and provides a highly efficient device which can be quickly and easily adjusted to drill and ream holes through the shell for vertical or circumferential joints in tubular structures.

Having thus described my invention, what I claim is:—

1. In a drilling machine, a mast comprising spaced vertical members, an arm pivotally mounted between said members, and a frame comprising spaced apart members pivotally and slidably attached between the spaced members forming the said arm.

2. In a drilling machine, a mast comprising spaced members, an arm comprising spaced members pivotally mounted between the mast members, sliding members in said arm, a frame carrying the drill actuating mechanism pivotally suspended from the sliding members, and means for moving the sliding members in the arms.

3. In a drilling machine, a mast comprising spaced members, means for rotatably supporting the mast in a vertical position, an arm comprising spaced members pivotally secured between the mast members, slide members mounted in the arm, a frame carrying the drill actuating mechanism, said frame being pivotally suspended between the slide members, and means for moving the slide members within the arm.

In witness whereof, I have hereunto set my hand.

HERBERT W. McMILLAN.
